MANUFACTURE OF PROFILED MATCHES

Felix Käppler, Freiberg, Germany

Application November 6, 1933, Serial No. 696,861
In Switzerland December 26, 1932

2 Claims. (Cl. 144—51)

This invention relates to a method and device for profiling match splints consisting of paper, board, cardboard or similar materials and formed on one or both sides of an endless band of material.

Matches profiled according to the invention have a conical pointed shape and are produced from an endless band by a device comprising different profiled rollers.

10 Compared with the known profiled matches, the matches produced according to the invention afford the advantage that the part of the match subjected to greatest stress while igniting is doubled longitudinally and thereby reinforced and that, owing to their shape, which is tapered toward the outer end, the splints, when dipped into the igniting composition, are provided with very small heads, whereby a considerable saving in igniting mass is effected.

20 By way of example, the invention is illustrated in the accompanying drawing, in which Figure 1 is a side view of the cutting and profiling device; Fig. 2, a view of a profiled match splint of which only a small part has conical shape; Fig. 3, a 15 view of a match splint having a larger part thereof tapering to a point; Fig. 4, a view of a match splint having a conical shape over its entire length; Fig. 5, a diagram of several profiled match splints, one with a head, connected to a common base; Fig. 6, a cross section of the tip of a profiled match; Fig. 7, a view on a large scale, showing the cutting and profiling device; Fig. 8, a sectional view on a large scale of the first folding step on the cutting and profiling device substantially in a plane where the tip of the match is formed; Fig. 9, a sectional view on a large scale of the second folding step on the cutting and profiling device; Fig. 10, a sectional view on a large scale of the last folding and pressing step; Fig. 40 11 shows in a smaller scale a longitudinally sectional view of the cutting and profiling device of Fig. 7 and Fig. 12 shows in a smaller scale a longitudinally sectional view of the last folding device of Fig. 10.

45 Referring to the drawing, the match splints 2 formed on one or both sides of an endless band of material 1 are made conical by folding or pressing together the two corners 3 at the top end of the splints. Conical shape may be imparted to the splints over their entire length, as shown in Figs. 4 and 5, or only to a part thereof, as indicated in Figs. 2 and 3. When a match splint formed according to the invention is dipped into igniting composition in known manner, the tip 4 formed thereby will be extremely small and

fully surround the compressed corners 3, as shown in Fig. 6. Being dried, the match splint will permanently retain the conical form imparted to it.

The conical or tapered splints are made on a cutting and profiling device shown in Fig. 1 by the steps shown in Figs. 7, 8, 9, and 10, the steps involving the employment of various folding and pressing rollers 5, 6, and 7 constructed like toothed wheels and axially disposed around a cutting roller 10 provided with a large number of cutters 8 and a counter-pressure roller 9. During the cutting step shown in Fig. 7 transverse cuts, appropriately spaced apart, are made in the material 1 by the cutters 8 to form the individual splints or matches, and as the splints connected to a common base cannot be displaced, perfect conical or tapered shape is imparted in the subsequent operations to each individual splint. The folding and pressing rollers placed around the cutting roller 10 may vary in number and diameter, though preferably three of these rollers are provided whose diameter, according to their number, is much smaller than that of the roller 10.

50 The cutting and profiling device may comprise two frames 11 with plain bearings 12 for the cutting roller 10, with bearings 13 for the counter-pressure roller 9, bearings 14 for the folding roller 5 for carrying out the first folding step according to Fig. 8, with bearings 15 for the folding roller 6 for the second folding step, as indicated in Fig. 9; and with bearings 16 for the pressing roller 7 for carrying out the pressing step according to Fig. 10. 17 is a feeding table for the endless strip of material 1.

The device is driven by toothed wheels secured to the shafts of all rollers and having the same diameter as the latter. Drive is effected by the driving pulley 18 on the shaft of the roller 5 whence drive is transmitted by the toothed gear of the roller 5 to the gear of the cutting roller 10 and thence to the toothed wheels of the rollers 6, 7, and 9.

55 The profiling of each match splint takes place in stages by guiding the endless strip 1 over the table 17 to the cutting device by means of which the match splints are formed on one or both sides of the endless strip 1 and are forced between the cutters 8 and slightly deflected upwardly, in which position they pass to the folding and pressing members shown in Figs. 8, 9, and 10. During the first folding step according to Fig. 8 the top portions of the splints are preliminarily folded by the interchangeable teeth 19 of the

roller 5 which press them into the conical top portion of the recesses 20 illustrated in Fig. 11. During the second folding step according to Fig. 9 folding of the splints continues by means of the teeth 22 of the roller 6 and their interchangeable plungers 21 which press the top portions of the splints into the narrowed lower portion of the recesses 20. During the third and last step, according to Fig. 10, the top portions of the splints are fully pressed into the recesses 20 by the teeth 23 of the roller 7 so as to impart final shape to the matches. While the top portions of the splints are thus progressively pressed together the remaining portions of the splints, from the top portion toward the base, which is united with the strip 1, are automatically folded with increasing curvature toward the base, so that the base portion of the splint is almost flat. The Fig. 5 illustrates a series of matches produced in this manner. By means of a rail 24 having a tongue 25 disposed under the undivided endless strip 1 the individual profiled matches are lifted out of the recesses 20 and passed on to known devices for attaching tips.

If endless bands of inferior material which does not readily bend or fold are used, folding and pressing must be carried out by a larger number of steps by providing a greater number of folding and pressing rollers around the cutting roller.

I claim:—

1. Apparatus of the class described, comprising

ing supporting elements having bearings, a cutting roller mounted in certain of said bearings for rotation and having a plurality of longitudinal cutters and longitudinal recesses between the cutters, a counterpressure roller for said cutting roller mounted in other of said bearings, and a plurality of toothed folding and pressing rollers axially disposed around said cutting roller and each mounted in other of said bearings and having profiled teeth, the said profiled teeth of said folding and pressing rollers coacting with the longitudinal recesses of the cutting roller to fold each match splint longitudinally and impart tapered form thereto.

2. The herein described method of producing profiled matches from paper or the like, consisting in forming the splints on one side of an endless strip of material by cutting, positioning the splints between the cutting means, rotatably guiding the strip without relatively displacing the formed splints longitudinally, so folding the splints into cross sectionally substantially U-shaped form from near the tops thereof toward the bottoms as to impart tapered form thereto, pressing the corners of the splints together after the splints have been thus longitudinally folded, and then guiding the splints to tip forming means.

FELIX KÄPPLER. 30
